AIRCRAFT FUEL INJECTION SYSTEM

Harry J. Botterud, Jr., Tujunga, Frank I. Crittenden, Van Nuys, and Roger A. Fulton, Canoga Park, Calif., assignors, by mesne assignments, to The Bendix Corporation, South Bend, Ind., a corporation of Delaware
Filed Feb. 13, 1961, Ser. No. 88,825
5 Claims. (Cl. 123—119)

The present invention relates generally to the aircraft engine art and more particularly to a novel aircraft fuel injection system for piston-type aircraft.

Briefly stated, one embodiment of the present invention includes the combination of an impeller air intake section of a piston-type aircraft engine containing a right-angle passageway with arcuate turning vanes in the passageway, and a fuel injector nozzle positioned upstream of the right-angle passageway and the turning vane. The nozzle preferably extends normal to the flow of air and contains an opening at the inner end thereof for emitting fluid fuel in the form of a conical spray.

As is well known in the art, the use of float-type carburetors with piston aircraft engines has not been completely satisfactory because of icing problems and relatively low operational performance. Consequently, much time and effort has been directed toward the utilization of fuel injection systems with such engines. Some of the piston-type aircraft engines operate very satisfactorily when supplied with such systems, whereas others are not consistent in their operational characteristics. Thus, in one engine which includes an impeller air intake section having a right-angle passageway containing arcuate turning vanes downstream of the fuel regulator, a fuel injector nozzle placed in the right-angle passageway can be adjusted to operate satisfactorily for the one engine but the same position and adjustments will not operate satisfactorily on a different engine of the same type and size because of the differences in the internal dimensions of the crankcases.

It is an object of the present invention, therefore, to provide a novel aircraft fuel injection system for certain piston-type aircraft engines which will overcome the icing problems and low operational performance present when float-type carburetors are used therewith.

Another object is to provide such a system which will operate satisfactorily with all piston-type engines of a particular type and size. More particularly, it is an object to provide a fuel injector to impeller air intake section relationship which will provide satisfactory fuel injection operation regardless of the irregularities of the impeller air intake sections and the differences in internal dimensions thereof even when they are of the same size and design.

Yet another object is to provide a fuel injection system for piston-type aircraft engines which provides an improved fuel-air distribution over the fuel-air distribution achieved with a standard float-type carburetor. More particularly, it is an object to provide such an injection system in which there is as much as a fifty percent improvement in fuel distribution as compared with a conventional float-type carburetor.

Further objects and advantages of the present invention will be apparent from the following detailed description, reference being had to the accompanying drawings wherein a preferred embodiment of the present invention is shown.

In the drawings:

FIG. 1 is a front elevational view of the impeller air intake section of a piston-type aircraft engine provided with a novel fuel injection system constructed in accordance with the teachings of the present invention;

2

FIG. 2 is a vertical sectional view taken on the line 2—2 in FIG. 1; and

FIG. 3 is an enlarged fragmentary sectional view taken on the line 3—3 in FIG. 1.

As indicated hereinabove, the manufacturing tolerances on the impeller air intake sections of piston-type aircraft engines are relatively large and therefore there is considerable difference between the internal dimensions of the cases even though they are for the same size and type of engine. It is this difference in manufacturers' tolerances on both external and internal dimensions which presented the greatest problem in providing a fuel injection system of universal application. This problem was solved by the instant construction which provides uniformly consistent fuel-air distribution in each engine regardless of the difference in impeller air intake section dimensions. As will be described more fully herein-after, this result was achieved by placing the fuel injector upstream from the right-angle bend and the arcuate turning vanes and spraying the fuel into the air stream in the form of a conical spray substantially normal to the flow of the air.

Referring to the drawing more particularly by reference numerals, 10 indicates a conventional impeller air intake section of a piston-type aircraft having associated therewith a fuel-injection system embodying the teachings of the present invention. The impeller air intake section 10 contains an inlet or outer end 12 and an inner end 14. Adjacent the inner end 14 is an engine impeller 16 and upstream of the impeller is a right-angle passageway 18 containing a plurality of radially spaced arcuate turning vanes 20.

Connected to the outer end of the impeller air intake section is the upper end of a tubular adapter 22 which contains a sidewall 24 with a smooth inner surface 26 and containing an outwardly extending cylindrical protuberance 28 with a flat mounting surface 30 for receiving a fuel injector nozzle assembly 32. A cylindrical passageway 34 extends through the protuberance from the inner surface 26 to the mounting surface 30.

The nozzle assembly 32 includes a housing 36 which is removably mounted on the surface 30 by any suitable means such as machine screws, and a nozzle 38 which extends through the passageway 34 and into the interior of the adapter 22. In one embodiment of the present invention, the inside diameter of the adapter 22 at the nozzle is about three inches, and the nozzle projects inwardly about one-half inch so that the ratio of projection to diameter is about one to six.

As shown in FIG. 3, the nozzle 38 contains a cone-shaped movable head 40 which provides a conical spray of fuel into the interior of the adapter 22, the movement of the head 40 relative to the nozzle body controlling the thickness or amount of fluid fuel in a conventional manner. The housing 36 contains a fuel supply inlet 42 which is in direct communication with the nozzle previously described, and a T-shaped servo fitting 44 which is in communication with the back side of a control diaphragm (not shown), the servo fitting including an inlet 46 and an outlet 48. One end of a fuel supply hose 50 is connected to the fuel supply inlet 42, one end of a servo hose 52 is connected to the inlet 46 of the servo fitting 44, and one end of a bleed hose 54 is connected to the servo fitting outlet 48. The other end of the bleed hose 54 is in communication with the fuel tank and the other ends of the fuel supply and servo hoses are connected to a fuel regulator or metering unit 56 which is fastened to the lower end of the tubular adapter 22 and which will now be described.

The metering unit 56 functions in a known manner to control the flow of fuel to the nozzle and the pressure

on the diaphragm previously described, and includes a throttle control arm 58, a mixture control arm 60, a main fuel inlet 62, a servo outlet 64 which is connected to the other end of the servo hose 52, and a fuel supply outlet 66 which is connected to the other end of the fuel supply hose 50.

In operation, fuel enters the metering unit 56 through the main fuel inlet 62 and passes therefrom through the servo hose outlet 64 and the fuel supply hose outlet 66. The fuel which passes through the servo hose 52 and into the servo fitting 44 acts upon the control diaphragm contained within the nozzle housing 36 and is then returned to the fuel tank (not shown) through the bleed hose 54.

On the other hand, the fuel which passes through the fuel supply hose 50 enters the nozzle housing through the inlet 42 and passes through the nozzle 38 into the interior of the adapter 22 in the form of a conical spray, as previously described. In the adapter, the fuel mixes with the incoming air and is directed through the passageway 18 by the arcuate turning vanes 20 and into the eye of the impeller 16. Beyond the impeller the fuel mixture is channeled through a manifold (not shown) or directly into a cylinder.

Because the fuel is injected in the stated manner upstream of the impeller air intake section, the difference in the dimensions between different impeller air intake sections of the same type and size does not adversely affect the fuel-air distribution, and therefor each installation achieves consistently good results as to fuel-air distribution and as much as a fifty percent improvement is achieved compared with conventional float-type carburetor systems.

Thus, it is apparent that there has been provided a novel aircraft fuel injection system for piston-type aircraft engines which fulfills all of the objects and advantages sought therefor. It is to be understood that the foregoing description and the accompanying drawings have been given only by way of illustration and example and that changes and alterations in the present disclosure which will be readily apparent to one skilled in the art are contemplated as within the scope of the present invention.

We claim:

1. In fuel supply apparatus for a combustion engine having a manifold in communication with a plurality of cylinders, an impeller for pressurizing air flowing to the manifold and an impeller air intake section containing a right angle passageway therethrough provided with arcuate turning vanes, the combination of tubular means connected to an inlet of the impeller air intake section and having a passageway therethrough for the passage of air and containing a side wall, a fuel injector nozzle mounted on said side wall and projecting into said passageway for injecting fuel into said tubular means substantially normal to the direction of air flow therethrough, a fuel conduit connected to supply pressurized fuel to said fuel injection nozzle, and control means operatively connected to said fuel conduit for controlling the flow of fuel therethrough to said nozzle.

2. In fuel supply apparatus for a combustion engine having a manifold in communication with a plurality of

cylinders, an impeller for pressurizing air flowing to the manifold and an impeller air intake section containing a right angle passageway therethrough provided with arcuate turning vanes, the combination of tubular means connected to an inlet of the impeller air intake section and having an opening therethrough for the passage of air and containing a side wall, a fuel injector nozzle mounted on said side wall and extending into the passageway substantially normal to the direction of air flow therethrough, a fuel conduit connected to supply pressurized fuel to said fuel injection nozzle, and control means operatively connected to said fuel conduit for controlling the flow of fuel therethrough to said nozzle.

3. In fuel supply apparatus for a combustion engine having a manifold in communication with a plurality of cylinders, an impeller for pressurizing air flowing to the manifold and an impeller air intake section containing a right angle passageway therethrough provided with arcuate turning vanes, the combination of tubular means connected to an inlet of the impeller air intake section and having an opening therethrough for the passage of air and containing a side wall, a fuel injector nozzle mounted on said side wall and extending into the passageway transversely to the air flow therethrough a distance substantially less than the radius thereof, said nozzle having an opening in the end thereof from which fuel is injected in the form of a conical spray to said air flow, and control means operatively connected to said fuel conduit for controlling the flow of fuel therethrough to said nozzle.

4. Fuel supply apparatus for a combustion engine having a manifold in communication with a plurality of cylinders, an air impeller for supplying air to the manifold and an impeller air intake section having a right angle passageway therethrough connected to supply air to the impeller, the combination of tubular means connected to the inlet of the impeller air intake section and provided with a side wall, control means including a venturi and an air throttle valve for controlling the flow of air to said tubular means, a fuel injector nozzle mounted on said side wall downstream from said venturi and air throttle valve and projecting into said tubular means normal to the direction of air flow therethrough, a fuel conduit connected to supply pressurized fuel to said fuel injector nozzle, means operatively connected to said fuel conduit for controlling fuel flow therethrough, and arcuate turning vanes operatively connected to the right angle passageway for guiding the flow of air-fuel mixture therethrough.

5. Fuel supply apparatus as claimed in claim 4 wherein said fuel injector nozzle projects into said passageway a distance such that the ratio of the amount of projection compared with the inside diameter of said passageway is in the ratio of about one to six.
